2 SHEETS—SHEET 2.

UNITED STATES PATENT OFFICE.

ANDREW M. BRUCE, OF IRA, MISSOURI.

RUBBER SHOE.

1,335,273.

Specification of Letters Patent. Patented Mar. 30, 1920.

Application filed July 26, 1919. Serial No. 313,517.

To all whom it may concern:

Be it known that I, ANDREW M. BRUCE, a citizen of the United States, residing at Ira, in the county of Laclede and State of Missouri, have invented certain new and useful Improvements in Rubber Shoes, of which the following is a specification, reference being had to the accompanying drawings.

Rubber shoes are indispensable articles of 10 footwear for wet and snowy weather, owing to their waterproof qualities, but one of the great objections to such footwear is that they cause the feet to sweat considerably, more so with some persons, than with others, 15 particularly because their feet perspire more than those of others, especially when the feet are heavily clad.

Therefore, this invention aims to provide 20 an article of footwear, which may be used as a rubber shoe, or as a lining for the old style shoe, and when employed as in the latter case, it is worn on the inside of the shoe and adapted to receive the foot. However, in the former use, namely as a rubber 25 shoe proper, the sole of the shoe is designed to be more or less heavy, in order to provide a firm tread surface. Furthermore, it is the aim to construct the shoe, whether used as such, or as a lining, with means, in order to 30 thoroughly ventilate the feet, namely, to permit a thorough circulation of air between the feet and the interior of the shoe, in order to prevent excessive sweating or perspiring of the feet.

The invention further aims to provide an 35 improved, simple, efficient and practical shoe or lining, which may be manufactured for a relatively low cost and sold at a reasonable profit.

The invention further aims to afford a 40 shoe of this character made up of an interior smooth portion around the foot, the ankle and a portion of the leg above the ankle, and an exterior corrugated piece having 45 its corrugations cemented and vulcanized to the interior piece, so arranged that the channels between the corrugations and the interior piece are communicatively connected with a hollow sole, the hollow of which 50 communicatively connects with the interior of the shoe, thereby permitting of a thorough circulation of air through the channels, the hollow of the sole, and into the interior of the shoe around the foot,

thereby avoiding excessive sweating or perspiring of the feet. 55

The invention further aims to provide a hollow sole, made up of upper and lower portions having intermediate cushions, thereby cushioning the foot at every step 60 of the wearer, and such cushion causing a compression of the hollow sole intermittently, so that an intake and an escape of air at every step of the wearer, permits of a thorough circulation of air around the foot. 65

The invention further aims to provide a 70 shoe of this character, which may be constructed to extend a trifle above the ankle in some cases, or may be constructed in the form of a shoe having a legging extension, which also has corrugations forming channels communicatively connecting with the hollow of the sole of the shoe.

The invention further aims to construct 75 a shoe of any suitable rubberized fabric, preferably a composition of canvas and rubber or the like, and made up of sections of such material, the parts being rubber cemented and vulcanized, so as to hold the parts together. 80

The invention further aims to provide secure fastening means for the various joints between the pieces or parts of the shoe or the lining, such as strips of rubberized tape or the like, that is a material consisting of 85 a composition of fabric such as canvas and rubber, said strips being rubber cemented and vulcanized on the seams between the pieces or parts of the shoe or lining.

The invention further aims to afford a 90 construction of shoe, which may be of the low quarter type, namely a little below the ankle, and in this case, the shoe may be worn on the exterior of an ordinary leather shoe. However, in this case, the foot 95 proper will not be in direct contact with the circulation of air, but instead the air will circulate under the sole of the leather shoe.

The invention further aims to afford a 100 shoe of this kind, which, as before stated, may be constructed with a legging extension, and in this case, the front portion of the legging is provided with an opening to be laced in order to be closed, there being a suitable covering or tongue or intermediate 105 piece (which has folds) between the laced edges of the openings and the leg of the wearer. By means of the folds in this

tongue or intermediate piece, a thorough circulation of air may travel down the tongue or inner piece and the leg, and thereby circulate through the hollow sole.

5 The invention further aims to provide an opening at the rear of the shoe, particularly adapted for facilitating the pulling on and taking off of the shoe, namely to permit of an easy insertion or extraction of the foot into and from the shoe. This opening also 10 prevents the shoe from excessively rubbing the ankle, that is allows the shoe to fit more or less loose around the ankle, thereby also allowing a circulation of air through the 15 opening, between the inner surface of the shoe and the foot.

The invention further aims to provide a flap or tongue at the rear of the shoe, to cover the aforesaid opening at the rear, to 20 keep out the wet and dampness.

The invention further aims to provide a shoe of this character, which comprises a vamp portion of corrugated material, and a corrugated upper, which are adhesively 25 united across the instep of the foot by rubber cement and a vulcanized rubberized strip, and to apply this vulcanized rubberized strip, it is caused to be formed into corrugations, owing to fitting into the exterior 30 corrugations of the vamp and the upper, thereby communicatively connecting the inner channels of the corrugated vamp and upper, allowing a circulation of air therethrough. If desired, the united edges of 35 the vamp and the upper may preferably spread out, instead of corrugated, though not necessarily, thereby permitting the rubberized tape to be fastened to the adjacent edges of the vamp and the upper, without 40 the tapes becoming corrugated to correspond with the corrugations of the vamp and the upper.

While the design and construction at 45 present illustrated and set forth is deemed preferable, it is obvious that as a result of a reduction of the invention to a more practical form for commercial purposes, the invention may be susceptible to changes, and the right to these changes is claimed, provided they are comprehended within the 50 scope of what is claimed.

The invention comprises further features and combination of parts, as hereinafter set forth, shown in the drawings and claimed.

55 In the drawings:

Figure 1 is a view in perspective of a rubber shoe, including a legging extension, and being constructed in accordance with the invention.

60 Fig. 2 is a front elevation of a portion of the shoe, at a point where the legging extension extends from the upper of the shoe, showing the detail construction between the upper of the shoe and the legging extension.

65

Fig. 3 is a horizontal sectional view on line 3—3 of Fig. 1, showing the seam in the front adjacent the instep portion of the shoe, and showing the opening at the rear, that is opposite the front seam, showing the covering flap on the interior, and the tape of the seam at the lower portion of the heel of the shoe.

Fig. 4 is a vertical sectional view on line 4—4 of Fig. 1, more clearly showing the 75 construction of the shoe and the legging extension, showing communicative connections between the channels of the corrugations and the hollow sole.

Fig. 5 is a vertical sectional view on line 80 5—5 of Fig. 1, showing the manner of the construction of the shoe at right angles to that shown in Fig. 4, also showing the communicative connection between the channels of the corrugations and the hollow of the 85 sole.

Fig. 6 is a sectional view on line 6—6 of Fig. 5.

Fig. 7 is a view of a rubber shoe with the legging extension omitted, otherwise the 90 construction of this shoe is the same as the lower part of the shoe in the other figures.

Referring to the drawings, 1 designates the sole of the shoe or lining as a whole, and this sole comprises the upper and lower 95 pieces 2 and 3, which may be constructed of any suitable material, preferably rubberized fabric, such as a composition of canvas and rubber. The pieces 2 and 3 may be any suitable shape, preferably to conform to the 100 outline of the bottom of the foot. The upper piece is provided with a plurality of perforations or openings 4, and the upper and lower pieces are held spaced apart, to provide a hollow 5, by means of the cushion 105 members 6. These cushion members may be constructed of any suitable material, preferably rubberized fabric, such as a composition of canvas and rubber, or may be constructed of rubber alone, and may be any 110 suitable shape, preferably cylindrical, though not necessarily. By means of these cylindrical spacing members or cushions 6, the upper piece may move yieldably toward the bottom or sole piece proper. These spacing 115 or cushioning members may be rubber cemented or vulcanized and intermediate the upper and lower pieces 2 and 3. A vamp 7 is provided, and it consists of the inner and outer pieces 8 and 9. The inner piece 120 8 is smooth, or in other words plain, while the outer piece 9 is corrugated, as shown at 10 in Fig. 1. These corrugations extend in the directions as shown, and certain portions of the corrugations are rubber cemented or vulcanized to the inner plain piece, 125 so as to afford channels between certain of the corrugations and the plain piece. The inner plain piece 8 is rubber cemented or vulcanized or otherwise secured in any suit- 130

able manner to the upper or inner piece of the sole, as shown at 11. The edge portion of the outer piece, that is adjacent the forward portion of the bottom piece of the sole, 5 is securely connected or seamed to the bottom piece of the sole, by means of a rubberized strip or tape of fabric 12, rubber cemented and vulcanized securely in place, providing a waterproof seam.

10 The upper 13 of the shoe comprises the inner and outer side pieces 14 and 15. The inner piece 14 is plain and smooth, the same as the inner piece of the vamp, while the outer piece is corrugated or fluted as shown 15 at 16, the same as the outer piece of the vamp. Portions of certain of the corrugations of the outer pieces 15 of the upper are rubber cemented or vulcanized as at 17 to the inner piece of the upper. These inner 20 and outer pieces 14 and 15 can be made of any suitable material, preferably rubberized fabric such as a composition of canvas and rubber or any other suitable fabric material. The inner side pieces 14 are connected as 25 shown at 18, by means of a rubberized fabric tape or strip 19. This strip or tape 19 is rubber cemented and vulcanized in place, thereby providing a smooth seam on the interior of the shoe. However, this seam extends only but a short distance upwardly, 30 for instance it terminates approximately adjacent the ankle of the wearer. Also, the lower edges of the outer side pieces of the upper are connected to the lower piece of 35 the sole, by means of a rubberized tape or strip 20, which is rubber cemented and vulcanized into place. In fact, the tape or strip 20 is a continuation of the strip or tape 12. The rear opposite edges of the 40 outer piece 15 of the upper are connected by means of a rubberized strip or tape of fabric or other material 21, which is rubber cemented and vulcanized in place. This strip 21 extends upwardly to the same distance 45 as the inner strip 19. It will be noted that the adjacent edges of the inner and outer pieces 14 and 15 of the upper, that is the rear portion of the shoe, are adhesively connected as shown at 22 by means of rubber cement and vulcanizing. However, the 50 adjacent edges at this point for a distance from b to c are disconnected, thereby causing an opening to be formed at the upper portion of the rear of the upper. By means 55 of this opening, the pulling on and pulling off of the shoe is greatly facilitated. In fact, by means of this opening the foot can be easily inserted in the shoe. Furthermore, by means of this opening, the upper of the 60 shoe is prevented from rubbing the ankle. In fact, the upper of the shoe loosely fits about the ankle and prevents rubbing. However, this opening is covered by a flap or piece 24, which is suitably connected, by 65 means of rubber cement and vulcanizing,

as shown at 25 to the inner portion of one of the inner pieces of the upper, while the other portion of the strip or flap overlies the rear part of the opposite side of the upper, that is on its inner face.

The inner and outer pieces 8 and 9 of the vamp, and the inner and outer side pieces of the upper are connected, by means of the tapes or strips 26 and 27. The inner tape or strip 26 is rubber cemented and vulcanized 70 as at 28 to the inner pieces of the vamp and the upper, thereby providing a smooth seam. It is obvious that where the tape or strip 27 is rubber cemented or vulcanized to the outer pieces of the vamp and the upper, as shown 75 at 29, the corrugations of the outer pieces of the vamp and the upper are flattened out, so that the strip or tape 27 may be secured in place. It is further obvious that the corrugations of the outer pieces of the vamp and 80 upper are arranged to register, so that the channels of the registered corrugations communicatively connect, and since the corrugations of the vamp communicatively connect with the hollow of the sole, then a thorough 85 circulation of air is allowed to pass through the corrugations of the vamp and the upper and into the hollow of the sole. It is also 90 obvious that as the weight of the wearer depresses the upper pieces of the sole, air is 95 drawn in and allowed to escape, at each step of the wearer. The air alternately acts in this manner, thereby allowing a thorough circulation of air about the foot, since the hollow of the sole is in communicative connection with the interior of the shoe. It is also to be remembered that where the continuous tape of strip 12 or 20 connects to the outer pieces of the vamp and the upper, the 100 corrugations are also flattened out, in order 105 that the strip or tape may be properly connected or secured in place. The forward adjacent edges of the outer pieces of the upper are united by means of the rubberized strip or tape 31, which is rubber cemented and 110 vulcanized in place. The corrugations at this point, that is where the rubberized or composition of canvas and rubber strip 31 is secured, the corrugations of the outer pieces of the upper are flattened, so as to facilitate 115 the connection of the strip or tape in place. The forward adjacent edges of the inner pieces of the opposite sides of the upper are connected in a similar manner, as by means of a strip or tape 32, which is also rubber 120 cemented and vulcanized in place.

It will be observed that the inner side pieces 14 of the upper as shown in Fig. 7 terminates a short distance above the ankle of the wearer, thereby providing a lower 125 shoe than that shown in the other figures of the drawing. However, in the other figures, a legging extension is provided, and this legging extension 33 comprises an inner piece 130 of rubberized fabric, such as a composi-

tion of canvas and rubber. This inner piece 34 extends about the leg of the wearer, and its lower edge joints the upper edges of the inner side pieces of the upper, as shown at 5 35, there being a strip or tape 36 covering the joint 35. This strip or tape 36 is rubber cemented or vulcanized in place, thereby providing a very secure smooth seam between the parts. This legging extension also 10 includes outer side pieces 37, which have their rear adjacent edges abutting, as shown at 38, there being a vertical strip or tape 39 rubber cemented, as shown at 40 to connect the opposite outer side pieces of the legging 15 extension. The lower portions of the outer opposite side pieces of the legging extension are connected to the upper portions of the upper corrugated pieces of the upper of the shoe, as by means of the strip or tape 41 of 20 rubberized fabric, for instance a composition of canvas and rubber, or any other suitable material adapted to exclude water or moisture. This strip or tape 41 is rubber cemented and vulcanized to the adjacent parts. 25 This tape or strip extends about the upper portion of the upper of the shoe as shown clearly in Fig. 1. The lower end of the strip or tape 39 abuts the upper rear portion of the tape or strip 41 as shown clearly in Figs. 30 1 and 5. Interposed between the inner and outer pieces 34 and 37 of the legging extension is a corrugated or fluted piece 42, the corrugations of which are rubber cemented and vulcanized at 43 and 44 to the adjacent 35 faces of the inner and outer pieces of the legging extension. The corrugations of this intermediate piece form channels, which register with, and therefore communicatively connect with certain of the corrugations of the 40 outer side pieces 15 of the upper, thereby permitting a thorough circulation of air from a point exteriorly of the upper portion of the legging extension and through the upper, through the vamp, and also 45 through the upper and through the hollow of the sole, therefore it is obvious that the foot of the wearer may be thoroughly ventilated. An intake and escape of air alternately occurs, incident to each step of the 50 wearer, that is as pressure is applied on the upper piece of the sole, yieldably crushing the cushions between the upper and lower pieces of the sole, thereby causing intakes and ejections of the air. 55 The forward edges 45 of the inner and outer pieces of the legging extension are rubber cemented and vulcanized at 46, so as to secure the edge portions of such pieces securely together. Additional tapes or strips 60 47 are similarly connected to the outer faces of the outer pieces 37 of the legging extension near the edge portions 45, there being suitable perforations 48, (for instance, which are formed through the strips 47 and the 65 edge portions 45), for the reception of a

suitable lacing, whereby the legging extension may be drawn tightly about the leg. A tongue or cover piece 49 spans the opening between the edge portions 45, and this tongue is also constructed of any suitable rubberized fabric, or a composition of canvas and rubber or the like, and is provided with a plurality of folds, so as to permit of a circulation of air downwardly between the legging extension and the leg of the wearer. 70 The edge portions of this tongue are rubber cemented in any suitable manner, as shown at 50 to the inner face of the inner piece 34 of the legging extension. The lower part of the tongue is fastened under the strip or 80 tape 36, as by means of rubber cementing and vulcanizing.

The invention having been set forth, what is claimed as new and useful is:

1. In a shoe or lining, the combination with a hollow cushion sole, the inner wall of which having perforations of communication with the interior of the shoe, of an upper and a vamp for said sole, having channels of communication with the hollow of the sole, the channels of the upper being open to the atmosphere, and extending therefrom upwardly of the vamp and the upper of the shoe, thereby permitting a circulation of air from the exterior through the sole and into the interior of the shoe, the upper of the shoe having an opening at the rear through which air may pass into the shoe to insure a circulation of air through the sole. 90
2. In a shoe or lining, the combination with a hollow cushion sole, the inner wall of which having perforations of communication with the interior of the shoe, of an upper and a vamp for said sole, having channels of communication with the hollow of the sole and extending therefrom upwardly of the vamp and the upper of the shoe, thereby permitting a circulation of air from the exterior through the sole and into the interior of the shoe, and a legging extension rising upwardly from the upper of the shoe and provided with channels of communication with the channels of the upper of the shoe, the channels of the legging extension being open to the atmosphere, said legging extension being closed at the rear and having a laced opening at the front. 100
3. In a shoe or lining, the combination with a hollow cushion sole, the inner wall of which having perforations of communication with the interior of the shoe, of an upper and a vamp for said sole, having channels of communication with the hollow of the sole and extending therefrom upwardly of the vamp and the upper of the shoe, thereby permitting a circulation of air from the exterior through the sole and into the interior of the shoe, and a legging extension rising upwardly from the upper of the shoe and provided with channels of communication with the channels of the upper of the shoe, the channels of the legging extension being open to the atmosphere, said legging extension being closed at the rear and having a laced opening at the front. 110
4. In a shoe or lining, the combination with a hollow cushion sole, the inner wall of which having perforations of communication with the interior of the shoe, of an upper and a vamp for said sole, having channels of communication with the hollow of the sole and extending therefrom upwardly of the vamp and the upper of the shoe, thereby permitting a circulation of air from the exterior through the sole and into the interior of the shoe, and a legging extension rising upwardly from the upper of the shoe and provided with channels of communication with the channels of the upper of the shoe, the channels of the legging extension being open to the atmosphere, said legging extension being closed at the rear and having a laced opening at the front. 120
5. In a shoe or lining, the combination with a hollow cushion sole, the inner wall of which having perforations of communication with the interior of the shoe, of an upper and a vamp for said sole, having channels of communication with the hollow of the sole and extending therefrom upwardly of the vamp and the upper of the shoe, thereby permitting a circulation of air from the exterior through the sole and into the interior of the shoe, and a legging extension rising upwardly from the upper of the shoe and provided with channels of communication with the channels of the upper of the shoe, the channels of the legging extension being open to the atmosphere, said legging extension being closed at the rear and having a laced opening at the front. 130

munication with the channels of the upper of the shoe, the channels of the legging extension being open to the atmosphere, said legging extension being closed at the rear 5 and having a laced opening at the front, said laced opening having a covering tongue provided with a plurality of folds.

4. In a shoe of the kind set forth, the combination with a sole comprising upper and lower pieces having spacing cushion members therebetween, the upper piece having perforations, thereby communicatively connecting the interior of the shoe and the space between the upper and lower pieces of the 10 sole, of a vamp having channels communicatively connected to the space in the sole, said vamp having connecting means with the sole, an upper having channels communicatively connecting with the channels of the 15 vamp, the channels of the upper being open to the atmosphere, and the space of the sole, means connecting the upper to the sole, and means for connecting the upper to the vamp. 20

5. In a shoe of the kind set forth, the combination with a sole comprising upper and lower pieces having spacing cushion members therebetween, the upper piece having perforations, thereby communicatively connecting the interior of the shoe and the 25 space between the upper and lower pieces of the sole, of a vamp having channels communicatively connected to the space in the sole, said vamp having connecting means with the sole, an upper having channels communicatively connecting with the channels of the 30 vamp, the channels of the upper being open to the atmosphere, and the space of the sole, means connecting the upper to the sole, and means for connecting the upper to the vamp. 35

40 to the vamp, the rear part of the upper having at its rear portion an opening, thereby permitting air to pass into the shoe to insure a circulation of air through the hollow of the sole.

45 6. In a shoe of the kind set forth, the combination with a sole comprising upper and lower pieces having spacing cushion members therebetween, the upper piece having

perforations, thereby communicatively connecting the interior of the shoe and the space 50 between the upper and lower pieces of the sole, of a vamp having channels communicatively connected to the space in the sole, said vamp having connecting means with the sole, an upper having channels communicatively connecting with the channels of the 55 vamp, and the space of the sole, means connecting the upper to the sole, and means for connecting the upper to the vamp, a legging extension rising upwardly from the upper 60 of the shoe, said legging extension having channels communicatively connecting with the channels of the upper, the channels of the legging extension having their upper ends open to the atmosphere. 65

7. In a shoe of the kind set forth, the combination with a sole comprising upper and lower pieces having spacing cushion members therebetween, the upper piece having perforations, thereby communicatively connecting the interior of the shoe and the space 70 between the upper and lower pieces of the sole, of a vamp having channels communicatively connected to the space in the sole, said vamp having connecting means with the 75 sole, an upper having channels communicatively connecting with the channels of the vamp, and the space of the sole, means connecting the upper to the sole, and means for connecting the upper to the vamp, a legging 80 extension rising upwardly from the upper of the shoe, said legging extension having channels communicatively connecting with the channels of the upper, the channels of the legging extension having their upper 85 ends open to the atmosphere, said legging extension having a laced opening at its forward portion, and a folded tongue covering said laced opening.

In testimony whereof I hereunto affix my 90 signature in the presence of two witnesses.

ANDREW M. BRUCE.
